UNITED STATES PATENT OFFICE.

GEORGE H. GILMAN, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

DRILLING-MACHINE.

1,252,374.

Specification of Letters Patent.

Patented Jan. 1, 1918.

Application filed July 5, 1912. Serial No. 707,714.

To all whom it may concern:

Be it known that I, GEORGE H. GILMAN, a citizen of the United States, and a resident of Claremont, county of Sullivan, State of New Hampshire, (whose post-office address is Claremont, New Hampshire,) have invented an Improvement in Drilling-Machines, of which the following description, in connection with the accompanying drawings, is a specification, like characters on the drawings representing like parts.

My invention relates to apparatus for drilling deep holes, being more particularly, though not necessarily exclusively, concerned with quarrying or mining drills of that type in which the drill tool with its drill-bit is sunk bodily into the hole as it is being drilled. My invention will be best understood by reference to the following specification, when taken in connection with the accompanying illustration of one specific embodiment thereof, while its scope will be more particularly pointed out in the appended claims.

Referring to the drawings:—

Figure 1 is an elevation of a specific drilling apparatus embodying my invention, with the pressure fluid conduit partly broken away, and showing the drill sunk partly into a drilled hole in the stone or other material, the latter being shown in section;

Fig. 2 is an elevation of the drilling apparatus partly broken away, as viewed from the right-hand side of Fig. 1;

Fig. 3 is a plan section on an enlarged scale on line 3—3 of Fig. 1, illustrating the rotating mechanism and its driving motor;

Fig. 4 is a sectional view partly in elevation on an enlarged scale on line 4—4 of Fig. 2;

Fig. 5 is a detail sectional view on line 5—5 of Fig. 4;

Fig. 6 is a detail sectional view on line 6—6 of Fig. 4;

Fig. 7 is a detail sectional view on line 7—7 of Fig. 4;

Fig. 8 is an enlarged detail elevation partly in central vertical section of the upper portion of the pressure-fluid conduit illustrating a swivel joint; and

Fig. 9 is a sectional view, partly in elevation, upon an enlarged scale on line 9—9 of Fig. 1.

Referring to the drawings, and to the em-

bodiment of my invention which I have there disclosed for illustrative purposes, I have there shown a drilling apparatus having a suitable drill tool 10, which may be of the impact-hammer type, provided with a drill-bit 11, provided with an axial hole 11^x to conduct exhaust pressure fluid to the cutting edge to expel the cuttings. The drill bit may be non-rotatably held in any suitable manner in a casing 12 of the drill tool, as by making the shank non-circular in cross section, as is usual in tools of this class. The drill tool may be electrically or mechanically driven, but herein is of the pressure fluid type, and is provided with a piston hammer 13, adapted to strike the upper end of the drill-bit 11 in a usual and well-known manner, the piston being reciprocated under the influence of a suitable pressure fluid, as for example compressed air, admitted to the tool through a suitable pressure-fluid conduit 14, the latter preferably having an axial or central attachment to the upper end of the tool. The tool casing 12 may be provided with one or more exhaust passages 12^x to conduct a part of the exhaust pressure fluid rearwardly to the keyways 20, which in turn conduct said fluid rearwardly past the keys 19 and outwardly and rearwardly into the drill hole. The air thus released into the hole, together with the air released through the hollow drill-bit to the cutting edge, serves to expel the dust and cuttings. The casing 12 of the drill may be made small enough in diameter to permit the escape of the cuttings, and if desired may be provided with longitudinal grooves 12¹ to prevent the formation of mud rings around the casing and to facilitate the escape of the cuttings. The detailed construction of the tool is of no particular consequence as bearing upon the broad principles of my invention, the construction of the tool shown, however, being similar in its general character to that shown in my prior United States Patent No. 853,921, dated May 14, 1907.

The pressure-fluid conduit 14 may be secured to the drill tool in any suitable manner, but I have herein shown for this purpose connecting devices which afford a means for quickly and conveniently, yet securely, attaching the conduit to the tool in such a manner that they shall not become disconnected by the vibration to which the

parts are subjected, while at the same time permitting the apparatus to be readily dismounted at will. To this end, I have provided a tubular plug 15, constituting a conduit, threaded into the upper end of the drill casing 12, and held against rotation with respect to the drill tool by suitable means to prevent the parts from unscrewing, herein a collar 16 suitably inter-engaging 5 with the plug 15 and the tool casing 12. In the present instance, this collar is provided with one or more teeth 17, normally engaging suitable recesses 18 provided in the tool casing 12, and is mounted to slide on the 10 plug 15 into and out of inter-engagement with the tool casing, but is held against rotation on said plug by one or more keys, or feathers, 19, freely movable in keyways 20 provided in the plug. Suitable means are 15 provided for normally holding the collar 16 in inter-engagement with the tool casing 12, herein a spring 21 bearing at one end against said collar, and at its other end against a shoulder 22 provided in the plug 15. By 20 this means, the tool casing 12 is normally locked against rotation with respect to the plug 15, and is thus prevented from unscrewing from the latter, and yet may be 25 readily unscrewed at will by simply raising 30 the collar 16 against the tension of the spring 21, to withdraw the teeth 17 out of engagement with the recesses 18.

The plug 15 may be secured to the conduit 14 in any suitable manner, but I have 35 herein shown these parts threaded together, the plug being provided with a reduced externally threaded portion 23, threaded into the interior of the conduit 14. As a means for locking the conduit and plug against 40 accidental unscrewing, I may provide the lower terminal portion of the conduit with a series of teeth 24, and the upper terminal portion of the plug with a series of teeth 25, herein in the form of ratchet teeth, one set 45 inclined in the opposite direction to the other, and having suitable engaging means to lock them against relative rotation. This locking means may consist of a collar or sleeve 26, embracing the terminal portions 50 of the conduit and plug, and provided with suitable means engaging the two sets of teeth, herein oppositely acting yielding spring pawls, or the like, 27 and 28, herein formed integral with the sleeve 26. These 55 may be conveniently formed by slotting the sleeve or collar 26, as shown in Fig. 1, thus forming tongues, which may be bent inwardly as shown in Figs. 5 and 6, suitably to engage the two sets of teeth 24 and 25. 60 Preferably the sleeve is slotted, as at 29, to facilitate its application to and removal from the conduit and plug.

Preferably the upper terminal portion of the conduit 14 is constructed in a manner 65 similar to the lower terminal portion just

described, and is similarly secured to a nipple 30. The conduit may receive its supply of pressure fluid from a suitable supply conduit 31, herein a usual form of flexible conduit or hose, having swiveled connection 70 with the conduit 14 so as to permit the latter to be rotated during the operation of the tool while allowing the supply conduit 31 to remain relatively fixed. This swiveled connection may be of any suitable construction, but herein there is connected to the flexible conduit 31 a tubular swivel member 32 provided with an outwardly extending lateral annular flange 35, abutting against the end of the nipple 30, and held in engagement therewith by suitable means, herein a collar 34 provided with an inwardly extending annular flange 33 encircling the swivel member 32. Interposed between the flanges 33 and 35 is a suitable packing 36 80 to prevent leakage of the pressure fluid. The collar 34 may be secured to the nipple 30 in any suitable manner, as by providing the collar with an internal thread threaded onto a corresponding thread formed externally upon the nipple. By this means, the collar may be adjusted to compress the packing 36 and insure a non-leaking though freely swiveling connection between the parts. The collar may be normally secured 90 in the desired position of adjustment by suitable means, herein a clamp-screw 37 passing through ears 38 provided on the collar. 95

The conduit 14 serves not only as a means 100 for conducting the supply of pressure fluid to the tool, but also as a shank by means of which the tool may be manipulated and held against lateral movement and rotated, while at the same time permitting the tool 105 and shank to be fed by gravity toward the work. As a means for vertically guiding the shank or conduit 14, and imparting a rotary movement thereto, I may provide a rotating mechanism and suitable motive 110 power means for operating the same, which will presently be described. Herein the rotating mechanism and its motor is mounted upon a tripod 39, which may be of any usual construction, having legs 40 and 41-41. 115 This tripod carries at its upper portion a swiveled head or shell 42, constituting a support for the rotating mechanism and its driving motor.

Referring now to the rotating mechanism 120 and its motor, the rotating mechanism preferably comprises a roller or other similar clutch, comprising a series of rollers or balls 43, engaging the periphery of the conduit 14, and mounted in a suitable cage 44 encircling the conduit. The cage 44 receives an intermittent rotary motion from a ring 45 swiveled in the head 42 and provided with suitable inclined depressions 46 to receive the balls or rollers 43, and serving to wedge 125 130

the latter into driving engagement with the conduit, when the ring is rotated in one direction, while permitting the rollers or balls to be freed from such driving engagement, upon a partial rotation of the ring in the opposite direction. Thus if the ring 45 be rotated contra-clockwise (Fig. 3), the balls or rollers 43 will be crowded into engagement with the conduit 14 so as to rotate the latter, while upon a return movement of the ring, the cage 44 with its rollers or balls 43 is rotated clockwise by suitable means, herein a spring 47 bearing at one end against a pin 48 engaging a tooth 49 on the cage, and located in a recess 50 provided in the ring 45, there being provided a suitable screw-threaded plug 51 to permit the introduction and adjustment of the spring. This spring serves to urge the balls or rollers 43 constantly toward one end of their respective recesses 46, thus preventing them from becoming wedged in the other ends of their respective recesses. By this means, the roller clutch mechanism just described is capable of guiding the conduit 14 and at the same time imparting a step-by-step rotative movement thereto, while permitting the tool to sink into the drilled hole.

The ring 45 may receive an oscillatory motion from a suitable motor, herein a pressure-fluid motor comprising a cylinder 52 and piston 53, the latter being suitably connected to the ring 45 to drive the same, and herein being provided for that purpose with a depression 54 which receives a gear tooth 55 formed on the ring. The motor may be of any suitable type, but herein is in the form of a simple valveless motor having a constant pressure-space 56 receiving a supply of pressure-fluid from a conduit 57. The constant pressure in the space 56 acts against a reduced portion 58 on one end of the piston 53, and hence tends to constantly urge the latter toward the left (Fig. 3). The opposite end of the cylinder 52 is provided with one or more ports 59 directly communicating with the atmosphere. Hence the piston 53 will be moved toward the left under the influence of the pressure-fluid on the small area of its reduced portion 58 until the latter passes beyond a port 60, whereupon communication is established between the port 60 and the constant pressure-space 56, and the pressure-fluid is conducted through the port 60 and through a passage 61 and port 62 to the left-hand end of the cylinder. Now, since the area of the left-hand end of the piston 53 is greater than that of the reduced portion 58, the pressure acting against the latter will be over-balanced and the piston will return to its initial position, whereupon the reduced portion 58 will cut off communication between the pressure supply space 56 and the port 60, and the pressure fluid at the left-hand end of the piston will

exhaust to the atmosphere through the ports 59. There may be provided a suitable vent 63 leading from the annular space about the reduced portion 58 to the atmosphere to permit the free entrance and exit of atmospheric air at this point and prevent the formation of a cushion. If desired, the cylinder ends may be provided with plugs 64 and 65, having cushioning springs 66 and 67 respectively, operating in a well-known manner to cushion the piston at each end of its stroke. The conduits 31 and 57 may be connected to receive their supply of pressure-fluid from a main supply conduit 68, and the supply of pressure-fluid to the tool and to the tool-rotating motor may be controlled by suitable valves 69 and 70 respectively. It will now be evident that if the drill tool be rotated to drill a hole into the quarry bottom, or other place, a step-by-step rotative movement may be imparted to the tool, so as to present the cutting edges of the drill-bit at a fresh place with each stroke, and at the same time the tool is permitted to be fed bodily by the action of gravity into the drilled hole to any desired depth within the range of the shank or conduit 14, and the latter will be properly guided and held against lateral movement during its rotation.

It will also be evident that the tool will continue to receive its proper supply of pressure-fluid through the use of the swiveled connection, without interfering in any way with its rotation.

My invention is not limited to the employment of any particular form of motive power, nor is the same limited to the employment alone of an impact drill member, as distinct from a reciprocatory drill. Where a reciprocatory drill is employed, however, preferably some means should be employed apart from the mere resting of the cutter on the bottom of the hole, for holding the tool in fixed relation to the bottom thereof.

While I have herein shown one embodiment of my invention for illustrative purposes, and have disclosed and described in detail the construction and arrangement incidental to one specific embodiment thereof, it is to be understood that the invention is limited neither to its specific embodiment herein shown, nor to the mere details or relative arrangement of parts, but that extensive deviations from the illustrated form or embodiment of the invention may be made without departing from the principles thereof.

Having thus described one embodiment of my invention, what I claim and desire by Letters Patent to obtain is:—

1. Drilling apparatus comprising in combination a bit; a burrowing percussive motor; a cylindrical shank extending rearwardly from said motor; said bit, said per-

5 cussive motor and said shank being connected for rotation as a unit; and frictional means directly engaging said cylindrical shank and adapted to permit longitudinal feeding movement of said shank relative to said frictional means while imparting intermittent rotary movement to said shank.

10 2. Drilling apparatus comprising in combination a bit; a burrowing percussive motor; a cylindrical shank extending rearwardly from said motor; said bit, said percussive motor and said shank being connected for rotation as a unit; and clutch

means directly engaging said cylindrical shank and adapted to permit longitudinal feeding movement of said shank relative to said clutch means while imparting rotary movement to said shank. 15

In testimony whereof, I have signed my name to this specification, in the presence of 20 two subscribing witnesses.

GEORGE H. GILMAN.
